UNITED STATES PATENT OFFICE.

THOMAS LOYND, OF WORCESTER, MASSACHUSETTS.

DESIGN FOR AN EAR FOR VESSELS.

SPECIFICATION forming part of Design No. 28,979, dated July 5, 1898.

Application filed April 13, 1898. Serial No. 677,500. Term of patent 14 years.

To all whom it may concern:

Be it known that I, THOMAS LOYND, a citizen of the United States, residing at Worcester, in the county of Worcester and State of Massachusetts, have invented and produced a new and original Design for an Ear for Vessels, of which the following is a specification, reference being had to the accompanying drawings, forming a part thereof, in which—

Figure 1 is a perspective view of an ear embodying the features of my design. Fig. 2 is an edge view of the same.

The features of the design consist in a base A, a neck B, and a head C. The base is laterally elongated, and the neck B rises from the upper portion of the base between its ends. The neck is so curved as to extend at its up-

per portion beyond the vertical plane of the upper surface of the base. The head C is in the same vertical plane with the upper portion of the neck, and its upper portion is stepped, being formed with a vertical extension a at one side and a convexed surface a' at the opposite side, meeting the extension at its base. An opening b appears in the head below the point where the extension and curved surfaces meet.

I claim—

The design for an ear for vessels herein shown and described.

THOMAS LOYND.
